US00D552542S

(12) **United States Design Patent** (10) **Patent No.:** **US D552,542 S**
Croley et al. (45) **Date of Patent:** **** Oct. 9, 2007**

(54) **MOBILE DEVICE BATTERY**

(75) Inventors: **Curt Croley**, Stony Brook, NY (US);
Carl Theleman, East Islip, NY (US);
JaeHo Choi, Whitestone, NY (US)

(73) Assignee: **Symbol Technologies, Inc.**, Holtsville, NY (US)

(**) Term: **14 Years**

(21) Appl. No.: **29/264,673**

(22) Filed: **Aug. 15, 2006**

(57) **CLAIM**

The ornamental design for a mobile device battery, as shown and described.

DESCRIPTION

FIG. 1 is a front elevational view of an embodiment of a mobile device battery showing our new design;

FIG. 2 is a side elevational view thereof;

FIG. 3 is a top plan view thereof;

FIG. 4 is a bottom plan view thereof; and,

FIG. 5 is a rear elevational view thereof.

The broken lines shown in FIGS. 1-5 are included for illustrative purposes only and form no part of the claimed design.
